UNITED STATES PATENT OFFICE.

MARTIN HEMLEB, OF ELIZABETH, NEW JERSEY, ASSIGNOR TO THE SINGER MANUFACTURING COMPANY, OF ELIZABETH, NEW JERSEY, A CORPORATION OF NEW JERSEY.

SAFETY DEVICE FOR ELECTRIC SEWING MACHINES.

Application filed April 3, 1923. Serial No. 629,570.

To all whom it may concern:

Be it known that I, MARTIN HEMLEB, a citizen of the United States, residing at Elizabeth, in the county of Union and State of New Jersey, have invented certain new and useful Improvements in Safety Devices for Electric Sewing Machines, of which the following is a specification, reference being had therein to the accompanying drawings.

10 This invention relates to electric sewing machines more particularly of the drop-head cabinet type. Machines of this type are customarily equipped with an electric motor and a manually operated motor-controller which is used to start and stop the motor and regulate the speed of the sewing machine.

The main object of the present invention is to provide a safety device whereby accidental starting of the motor is prevented when the machine is not in use.

The invention comprises the provision of a stop which is automatically moved to a position obstructing the movement of the motor-controller mechanism when the sewing head is dropped into the cavity of the cabinet; the stop releasing the motor-controller for manual operation when the sewing head is raised to operative position.

20 The motor-controller preferably comprises a rheostat connected in the motor circuit and a knee-shift connection for operating said rheostat. For the stop, advantage is preferably taken of the usual lifter-plate which swings downwardly into the cavity of the cabinet from a horizontal position flush with the top surface of the cabinet to a position below and transverse to such surface. The controller operating connections and lifter-plate are preferably so related that the lifter-plate locks such connections against movement when it is depressed to vertical position and releases such connections for operative movement when it is elevated to horizontal position. The invention is not to be understood, however, as limited to the employment of the movable lifter-plate for this purpose, as advantage may be taken of any part which must

necessarily move when the sewing head is dropped into the cavity of the cabinet, to shift a stop into the path of movement of an element of the controller operating mechanism.

In the accompanying drawings, Fig. 1 is a front elevation, partly in section, of a drop-head sewing machine cabinet outfit embodying the invention; the cabinet being open and the sewing head in sewing position. Fig. 2 is a front elevation of the cabinet with its parts in closed position. Fig. 3 is a transverse section through the cabinet on an enlarged scale and Figs. 4 and 5 are detail views showing a modification of the invention.

In the preferred embodiment of the invention, as illustrated in Figs. 1, 2 and 3, 1 represents a drop-head sewing machine cabinet of usual construction having legs 2 supporting the top-board 3 and side and end walls 4 which are disposed immediately below the top-board 3 and define a cavity within which the motor-driven sewing head 5 is housed when not in use. The usual means, including the hinge-pins 6, are provided whereby the sewing head may be raised out of the cavity to sewing position above the latter, in which position the front edge of the sewing machine base or bed-plate 5' rests upon the lip 7 of the hinged leaf 8.

The cabinet 1 is preferably provided with the usual lifter-plate 9 to partially sustain or balance the weight of the sewing head and make it easier for the user to raise the sewing head out of the cavity in the cabinet. The lifter-plate 9 is hinged at 10 to a bracket 11 secured to the cabinet 1, within the cavity of the latter, adjacent the rear end edge of the sewing machine bed-plate 5', so that the lifter-plate may extend alongside said rear end edge. The lifter-plate is formed with a lateral lug 12 which extends under the sewing machine bed-plate 5', as shown in Figs. 1 and 2. One end of a stout coil spring 13 mounted on the bracket 11 extends under the lifter-plate 9 and exerts upward pressure thereon to balance the

weight of the sewing head; all substantially as described in the United States patent to Diehl et al., No. 541,474.

The sewing head 5 preferably has 5 mounted thereon the electric motor 14 which, together with the sewing head, is received within the cavity of the cabinet 1 when the outfit is not in use. The motor 14 is preferably connected by means of a 10 belt 14' to the sewing machine balance-wheel 14''.

The motor is preferably controlled by means of a manually operated motor-controller which may comprise a rheostat 15 15 connected to a knee-shift 16. The rheostat 15 preferably comprises the usual resistor-connected contact points 17 over which plays the swinging contact arm 18 and is mounted in the iron box 19 which is secured 20 to the rear wall of the cabinet within the cavity of the latter. Mounted on the cover 20 of the box 19 is a lever 21 having a pin 22 which passes through a slot 23 in the cover 20 and is operatively connected to 25 swing the contact-arm 18. The spring 24 urges the lever 21 to "off" position.

The lever 21 is connected by means of a link 25 to the arm 26 formed at the rear end of a rock-shaft 27 mounted on pintles 28, 30 carried, respectively, by the rheostat box cover 20 and a bracket 29. The rock-shaft 27 is formed at its forward end with an arm 30 the head 31 of which is slotted to receive the knee-shift arm 16. The knee-shift arm 35 16 is pivotally held in the slotted head 31 by means of a screw 32 and may be shifted from operating position (full line position, Figs. 1 and 3) to non-operating position (full line position, Fig. 2, or dotted line position, 40 Fig. 3.)

The lifter-plate 9 may have fixed to its under side a stop-pin 33 which is so positioned and related to the arm 21 of the rheostat operating connections as to move into 45 the path of such arm, as shown in dotted lines in Figs. 1 and 3, when the sewing head is dropped into the cavity of the cabinet. When the stop-pin 33 occupies its dotted line position it blocks operative movement of the 50 knee-shift mechanism and prevents accidental starting of the motor. A safety device of this character is particularly desirable in an electric sewing machine cabinet outfit for household use where there is danger of children playing with the knee-shift lever 16 when the cabinet is closed. When an electric sewing machine is equipped with the present improvement it is unnecessary for 55 the user to pay particular attention to the disconnection of the supply cord from the lamp-socket or base-board receptacle when the machine is not to be used, as the mere act of dropping the sewing head into the cabinet locks the knee-shift against accident- 60 al operation.

In the modified form of the invention shown in Figs. 4 and 5, the pin 33 is omitted and an arm 34 is rigidly mounted or formed on the rock-shaft 27 in such a position that its path of movement intersects the lifter- 70 plate when the latter is in depressed position. The lifter-plate thus serves to block operative movement of the knee-shift mechanism when the cabinet is closed. The expression "manually operated" is used herein in its 75 usual broad sense meaning operated by the user of the machine; it being immaterial whether the operation is accomplished by movement of the operator's hand, arm, foot or knee.

Having thus set forth the nature of the invention, what I claim herein is:—

1. The combination with a drop-head sewing machine cabinet, a sewing head adapted to be housed within the cavity of such cabinet or raised to operating position above said cavity, and an electric motor for driving said sewing head, of a manually operated motor-speed regulating rheostat fixedly mounted within said cavity, and means operating automatically when the sewing head is dropped into the cavity of said cabinet to lock said rheostat against accidental operation.

2. In combination, a sewing machine cabinet, a motor-driven sewing head carried by said cabinet and movable from operating to housing position, a manually operated motor-controller fixedly carried by said cabinet independently of the sewing head and including a shiftable control element, and an automatic interlock when the sewing head is shifted to housing position, to lock said shiftable control element against movement.

3. In combination, a motor-driven sewing head, a drop-head cabinet having a cavity adapted for reception of said sewing head, a motor-controller fixedly mounted in said cavity, a knee-shift operatively connected at all times to said motor-controller, and automatic means for locking said knee-shift and connections against operative movement when the sewing head is lowered in said cavity.

4. In combination, a drop-head sewing machine cabinet, having a cavity, a motor-driven sewing head hinged to said cabinet to swing into and out of said cavity, a manually-operated motor-controller, and means movable with the sewing head into said cavity to a position blocking movement of an element of said manually-operated motor-controller.

5. In combination, a drop-head sewing machine cabinet having a cavity, a motor-driven sewing head hinged to said cabinet to swing into and out of said cavity, a spring-pressed lifter-plate adapted to move with the sewing head and partially sustain the weight of the latter, a manually-operated motor-

controller, and a stop movably associated with said lifter-plate and acting to block operative movement of said motor-controller when the sewing head is housed in said cavity.

6. In combination, a drop-head sewing machine cabinet including a lifter-plate, a motor-driven sewing head carried by said cabinet and movable with the lifter-plate

from sewing to housing position, a motor-controller including a knee-shift mechanism, and a stop carried by said lifter-plate in a position to block movement of an element of the knee-shift mechanism when the lifter-plate is in housing position.

In testimony whereof, I have signed my name to this specification.

MARTIN HEMLEB.

Certificate of Correction.

It is hereby certified that in Letters Patent No. 1,565,362, granted December 15, 1925, upon the application of Martin Hemleb, of Elizabeth, New Jersey, for an improvement in "Safety Devices for Electric Sewing Machines," an error appears in the printed specification requiring correction as follows: Page 2, line 102, claim 2, after the word "interlock" insert the words *connected to be operated*; and that the said Letters Patent should be read with this correction therein that the same may conform to the record of the case in the Patent Office.

Signed and sealed this 19th day of January, A. D. 1926.

[SEAL.]

WM. A. KINNAN,
Acting Commissioner of Patents.
